UNITED STATES PATENT OFFICE

THOMAS F. COTE, OF CLINTON, IOWA, ASSIGNEE TO COTE BROTHERS FUSE MANUFACTURING CORPORATION, OF CLINTON, IOWA, A CORPORATION OF DELAWARE

FUSE

Application filed November 12, 1928. Serial No. 318,852.

This invention relates to fuse plugs in general and more particularly to the type of plugs illustrated and described in connection with my prior U. S. Patent No. 1,520,561 of December 23, 1924.

Plugs of the above type have been in use heretofore but have not been so constructed that the fusible element within the fuse cartridge the latter being itself situated within the plug, could be inspected from the outside of the plug so as to determine conclusively whether or not said element had been burned out.

The primary object of this invention is accordingly to provide an arrangement whereby it is possible to inspect the fusible element within the cartridge which is itself within the plug, from outside the plug thereby rendering it unnecessary to remove the plug or cartridge to determine whether or not the fuse element has been burned out.

Other and further objects of this invention will be apparent as the same becomes better understood from an examination of the specification and claims in connection with the accompanying drawings, wherein:

Fig. 1 is a longitudinal sectional view of a fuse plug embodying this invention.

Fig. 2 is an end view of the cartridge removed from the plug.

Fig. 3 is an end view of the cartridge with the cap thereof removed.

Fig. 4 is a detailed view of the fusible element before the same is installed in the cartridge.

Referring to the drawings more particularly, numeral 1 indicates a body portion for the plug constructed of any suitable non-conducting material such as hard rubber or porcelain. The body portion 1 is hollow to provide a chamber 2 for the cartridge and is provided with a closed end 3 having a contact 4 extending therethrough for connecting the cartridge with the center terminal of a socket (not shown). The other end of the body portion 1 is formed open and is closed by a removable cover or body portion 5 of material similar to that of the portion 1. The cover or body portion 5 has seated therein a ferrule 6 the

side walls of which have pressed therein screw threads 7 adapted to cooperate with screw threads 8 formed within the portion 5 and also adapted to cooperate with screw threads 9 formed on the portion 1 to detachably secure the two body portions together. The screw threaded wall of the ferrule 6 extends out of the portion 5 and overlies a considerable part of the portion 1 and is adapted to have threaded connection with the usual socket (not shown). The portion 5 is provided with a centrally arranged opening 11 in its top wall in alignment with an opening 12 in the ferrule and the chamber 2. The opening 11 serves both as a vent and is flared at its outer end as at 13 to facilitate inspection of the interior of the body through said opening.

The fuse cartridge which is removably situated within the chamber 2 of the plug body is in the form of a sleeve 14 of insulation material, provided with a suitable vent opening intermediate its ends, spaced from the wall of the chamber and has its ends closed by metal caps 15 and 16 respectively of cup shape. The caps have frictional contact with the sleeve and are adapted to secure the ends of a fuse 17 against the ends of the sleeve. The ends of the fuse 17 are bent angularly and overlie the ends of the sleeve and are retained in engagement therewith by the caps, the major portion of the fuse extending diagonally through the sleeve. One end of the fuse instead of being directly bent over the adjacent edge of the sleeve to overlie the same is first bent so as to extend diametrically across the respective end of the fuse on the exterior of a disk 18 preferably of fibre which is frictionally engaged in the corresponding end 85 of the sleeve. The end of the fuse which passes diametrically across the corresponding end of the sleeve exteriorly of the disk 18 extends on over the outer edge of the sleeve and is bent in frictional engagement 90 with the cap 16. The portion of the fuse which is thus presented at the end of the sleeve is of reduced width as at 19 whereby the fuse is bound to blow out somewhere along this portion. In order that this end 100

may be inspected at all times from the exterior of the plug body the cap 16 is provided with an opening 21 which is closed by a pane 22 of mica or other suitable material which lies above the diametrically extending 5 reduced portion of the fuse element.

When the fuse plug is situated in the usual fuse socket (not shown) a circuit will be established between the ferrule, the cap 16 which is in engagement with the ferrule 10 at the marginal edges of the opening 12, the fuse 17, the cap 15 and the contact 4 adapted to be engaged by the latter cap.

In practice the portion 19 of the fuse element is painted a distinctive color, for instance red as shown, to render such portion more easily discernible from outside of the plug. Thus one may very readily determine whether or not the fuse is burned out because 15 it is bound to burn out in the painted portion 20 19 as the same is of reduced width.

The advantages and operation of the aforescribed plug with its removable cartridge provided with the fuse element which 25 may be inspected from without the plug 25 will be apparent without further description.

I am aware that many changes may be made without departing from the principles 30 of this invention and I therefore do not wish to be limited to the details shown or 35 described.

I claim:

1. A fuse plug comprising a body provided with an opening and a chamber in communication therewith, spaced contacts at each end of said chamber adapted for connection with corresponding terminals in an electrical circuit, a cartridge in said chamber comprising a hollow member, terminals 40 on opposite ends of said member in electrical contact with said contacts, and a fuse in said member connecting said terminals and having a narrow portion extending diametrically across the outer end of said member, the cartridge being constructed to render 45 said portion visible but sealed from and adjacent to said opening.

2. A fuse plug comprising a body provided with an opening and a chamber in communication with said opening, a pair of spaced contact elements in communication with the interior of said chamber adapted to electrically connect with corresponding 50 terminals in a circuit when the plug is in operative position therein and a cartridge in said chamber comprising a hollow member, terminals on said member in electrical contact with said elements, and a fuse element 55 in said member electrically connecting said terminals, a narrow portion of said fuse element being disposed diametrically across the outer end of said member in proximity to said opening and the remainder of the 60 fuse element being of substantially greater 65

width, said member being constructed so as to render said portion visible through said opening, the said portion being of a distinctive color.

3. In a fuse plug, a body having an opening at its outer end and a chamber communicating with the opening, circuit contact elements extending into opposite ends of said chamber, a cartridge adapted for mounting in said chamber having metal caps 70 at each end thereof contacting said contact elements and separated by a cylindrical hollow non-conductor, the cap at the outer end having an aperture registering with said opening and closed by a mica pane, and a fuse link contacting with one portion only 75 of the outer cap and extending therefrom diametrically across the outer end of the cartridge adjacent said mica pane and thence longitudinally of the cartridge into contact with the other cap, the portion of the fuse adjacent said mica pane being substantially narrower than the remainder of the fuse to assure blowing of the fuse in 80 that portion.

4. In a fuse plug, a body having an opening at its outer end and a chamber communicating with the opening, circuit contact elements extending into opposite ends of said chamber, a cartridge adapted for mounting in said chamber having metal caps 85 at each end thereof contacting said contact elements and separated by a cylindrical hollow non-conductor, the cap at the outer end having an aperture registering with said opening and closed by a mica pane, and a fuse link contacting with one portion only 90 of the outer cap and extending therefrom diametrically across the outer end of the cartridge adjacent said mica pane and thence longitudinally of the cartridge into contact with the other cap, the portion of the fuse adjacent said mica pane being substantially narrower than the remainder of the fuse to assure blowing of the fuse in 95 that portion.

In witness of the foregoing I affix my 100 signature.

THOMAS F. COTE.
